UNITED STATES PATENT OFFICE.

SIDNEY P. JONES, OF WACO, TEXAS.

ELECTRIC RAZOR.

Application filed April 13, 1925. Serial No. 22,806.

This invention relates to new and useful improvements in electric razors.

The object of the invention is to provide a razor of the vibratory type possessing certain highly advantageous and improved features, making for a more satisfactory and efficient device.

A particular object of the invention is to provide means for minutely regulating the 10 amplitude of the reciprocation of the blade.

An important object of the invention is to provide a simple and practical means of fastening the blade to the carrier posts; whereby it may be quickly and easily placed or removed and whereby it will be firmly and properly held in working relation to the guard teeth.

Another object of the invention is to provide a simple form of solenoid and a novel 20 means of adjustable connection between the core and the pitman, whereby the vibratory action may be controlled.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of a razor constructed in accordance with my invention,

Fig. 2 is a front elevation of the same,

Fig. 3 is an enlarged cross-sectional view 35 taken on the line 3—3 of Fig. 4,

Fig. 4 is an enlarged longitudinal sectional view taken on the line 4—4 of Fig. 2,

Fig. 5 is an end elevation of the razor,

Fig. 6 is an enlarged cross-sectional view 40 taken on the line 6—6 of Fig. 4,

Fig. 7 is an enlarged cross-sectional view taken on the line 7—7 of Fig. 4,

Fig. 8 is a detail of the blade latching post connection.

In the drawings the numeral 10 designates 45 an elongated head having a flat face 11 provided with a central recess 12. Along the side edges of the head contiguous to the face guard teeth 13 are provided. The head is integral with and offset laterally from a short neck 14 disposed centrally of a cap 15. The cap 15 has a screw threaded flange 16 engaging in the internally screw threaded end of a cylindrical handle 17.

The neck and cap have an axial bore 18. The head is formed on its rear side with

spaced bearing brackets 19. A cylindrical carriage 20 is mounted to slide in the bores of these brackets, which bores are preferably concentric to the bore 18. The carriage has 60 a shoulder 21 below the lower bracket 19 and is secured at this point to a pitman 22 extending through the bore 18. A coiled spring 23 surrounding the pitman is seated in a recess 24 in the neck and has its upper end engaged around the shoulder.

A keeper post 25 extends through a slot 26 in the head and has its reduced screw threaded end 27 engaged in the carriage 20. A latching post 28 extends through a slot 29 in the head and a slot 30 in the carriage and has its reduced screw threaded end 31 engaged in a plunger 32 slidable in a counterbore 33 in the end of said carriage. The plunger has a head 34 on its end extending 75 from the carriage; while its inner end compresses a coiled spring 35 confined in the bore 33.

Each post has an angular collar 36 integral therewith and resting on the bottom of the recess 12. Outwardly of the collar each post has a rounded head 37 and between the collar and the head, an annular groove 38. By pressing inwardly on the head 34 of the plunger 32, the latter is depressed against the tension of the spring 35 and the post 38 is moved in its slots 29 and 30 toward the post 25. By this arrangement a double edge blade 39 having a central longitudinal slot 40 may be engaged over the heads 37 and supported on the collars 36. When pressure on the plunger is released the post 28 is displaced, whereby the blade is pulled into the groove 38 by the keeper post 25 and is received in the groove 38 of the latching post 28; thus being securely and firmly held upon the collars. The grooves 38 are of course very shallow.

The blade is supported on the face 11 at each side of the recess 12 so that its cutting edges overhang the guard teeth 13, but may be carried entirely upon the collars 36 and spaced a fraction of an inch from the face. In order that the vibratory or reciprocative movement of the carriage 20 may be controlled, I provide a conical sump 41 in the carriage for receiving the conical end of a regulating screw 42 (Figs. 3 and 4) mounted in the head. In the sump 41 is mounted a bushing 41' of fibre or any other material suitable for the purpose of eliminating noise when the end of the screw contacts there-

with during the reciprocation of the carriage. By adjusting this screw into and out of the sump the space between the sides of the conical end and the walls of the sumps is varied and the travel of the carrier 20 is either shortened or lengthened. This is a very important feature because it assures a uniform travel of the blade and controls the spring action as well as the amplitude of the magnetic action.

In the handle I mount a solenoid 43 having a central well 44 in which a core 45 is slidable. The solenoid is confined by a disk 46 of electrical insulating material which receives the collar 16. The solenoid passes snugly through the disk and receives the screw threaded end of the pitman 22. A lock nut 47 mounted on said threaded end binds upon the end of the core and fastens the core against rotation. By this means the core may be adjusted so as to properly function when the solenoid is energized.

The solenoid rests upon an insulating disk 48 supported upon a shoulder 19' at the reduced lower end of the handle 17. The solenoid has terminal posts 49 (Fig. 2) depending through the disk and entering an attachment plug 50 which is inserted in the lower end of the handle. An electric current cord 51 is connected to the plug for supplying current to the magnet. The handle 17 is preferably formed of hard rubber or any other non-conductive material.

In using the razor the operator grasps the handle 17 and turns on the electrical current. Thus causes the solenoid 43 to be energized so that it attracts the core 45 and pulls the same downwardly. The solenoid illustrated is designed to be used with alternating current and therefore when the core has been pulled down it will be momentarily released, due to the pulsations of the current thereby permitting the spring 23, which was compressed on the down stroke, to expand and return the carriage. By this arrangement the stroke of the carriage will be effected in one direction by the solenoid and in the other direction by the spring. As the pulsations are rapid, so will the reciprocation of the carriage and blade be.

The throw of the carriage can be minutely controlled by the screw 42 and in actual practice, not over a $\frac{1}{2}$ of an inch is required, although this is subject to variation. The blade may be quickly released and replaced by simply depressing the plunger 32 and lifting the blade or laying it upon the collars 36. The whole device is comparatively light in weight and may be readily cleansed. The slots 26 and 29 are sufficiently long to prevent contact with their ends by the posts and this obviates noise.

What I claim, is:

1. In an electric razor, a handle, a cap at one end of the handle, having a bore

therethrough, a neck extending from the handle and through which the bore is continued, a solenoid in the handle, a core slidable in the solenoid, a pitman attached to the core and extending through the bore of the cap and neck, a head attached at one end to one side of the neck and extending longitudinally therefrom, a carrier mounted to reciprocate in the head, blade posts fast in the carrier and extending through the head for supporting a blade, and a latch connected with one of the posts.

2. In an electric razor, a head, a carrier mounted to reciprocate in the head, a solenoid for operating the carrier, a resilient means co-operating with the solenoid in reciprocating the carrier, and means engaged with the carrier for regulating the travel of the carrier and blade and adjustable to vary the said travel.

3. In an electric razor, a head, a carrier mounted to reciprocate in the head, a solenoid for operating the carrier, a resilient means co-operating with the solenoid in reciprocating the carrier, and means carried by the head and engaged by the carrier for regulating the travel of the carrier and blade and adjustable to vary the said travel.

4. In an electric razor, a head, a blade carrier mounted to reciprocate in the head, a blade keeper post carried by the carrier, a blade latching post carried by the carrier, means for reciprocating the carrier, and a blade fastened to and carried by said posts remote from the carrier and on the opposite side of the head.

5. In an electric razor, a head, a blade carrier mounted to reciprocate in the head, a blade keeper post carried by the carrier, a solenoid for actuating the carrier, resilient means co-operating with the solenoid to reciprocate the carrier, and a blade fastened to and carried by said posts remote from the carrier and on the opposite side of the head.

6. In an electric razor, a head, blade carrier mounted to reciprocate in the head, a blade keeper post carried by the carrier and having a blade-receiving groove, a blade latching post carried by the carrier and having a blade receiving groove, means for reciprocating the carrier, and a blade fastened to and carried by said posts remote from the carrier and on the opposite side of the head.

7. In an electric razor, a head, a blade carrier mounted to reciprocate in the head, a keeper post extending through the head and attached to the carrier, a latching post extending through the head and attached to the carrier, and means for reciprocating the carrier.

8. In an electric razor, a head, a blade carrier mounted to reciprocate in the head, a keeper post extending through the head and attached to the carrier, a latching post

extending through the head and attached to the carrier, a plunger mounted in the carrier, and a spring impelling the plunger and mounted in the carrier, the latch post being movable relatively of the carrier and secured to the plunger.

9. In an electric razor, a head, a blade carrier mounted to reciprocate in the head, a keeper post extending through the head and attached to the carrier, a latching post extending through the head and attached to the carrier, a plunger mounted in the carrier and engaged by the latching post, and means for reciprocating the carrier.
10. In an electric razor, a head, a blade carrier mounted to reciprocate in the head and having a sump, and a screw carried by the head and projecting into the sump, said screw being adjustable to vary the amplitude of the travel of the carrier.
11. In an electric razor, a head having a flat face, a blade carrier mounted in the

head and having means for supporting a blade contiguous to the face of the head, a handle on which the head is mounted, a solenoid in the handle, a connection between the solenoid and the carrier, and a coiled spring compressed when the carrier is moved by the solenoid.

12. In an electric razor, an elongated head having a flat face with teeth along each side thereof, spaced brackets carried by the head, a carrier reciprocating in the brackets, posts carried by the carrier and extending through the head, blade supports on the post at the face of the head, a plunger in the carrier connected with one of the posts, a pitman extending from the carrier, a handle supporting the head, a coiled spring surrounding the pitman between the head and the handle, and a solenoid in the handle having a core connected to the pitman.

In testimony whereof I affix my signature.
SIDNEY P. JONES.
